UNITED STATES PATENT OFFICE.

JAMES A. BRYAN, OF NEW BERNE, NORTH CAROLINA.

NUT-LOCK.

SPECIFICATION forming part of Letters Patent No. 427,040, dated May 6, 1890.

Application filed February 13, 1890. Serial No. 340,315. (No model.)

To all whom it may concern:

Be it known that I, JAMES A. BRYAN, a citizen of the United States, residing at New Berne, in the county of Craven and State of North Carolina, have invented certain new and useful Improvements in Nut-Locks; and I do hereby declare the following to be a full, clear, and exact description of the invention, such as will enable others skilled in the art 10 to which it appertains to make and use the same.

This invention relates to nut-locks; and it consists in the novel construction and combination of the parts hereinafter fully described and claimed.

In the drawings, Figure 1 is a side view of the nut-lock, showing it applied to the fish-plate bolts of a rail-joint. Fig. 2 is an end view of the nut-lock, showing the rail in cross-section. Fig. 3 is a detail plan view of the washer-plate.

A is the rail, B are the fish-plates, and C are the fish-plate bolts provided with nuts c. All of these parts are of ordinary approved 25 construction.

D is a washer-plate, provided with holes d, which are slipped over the ends of the bolts before the nuts are screwed upon them. E are similar ratchet-wheels, provided with 30 flanges e, and with shallow recesses e' for the nuts to fit into.

F is a post secured to the washer-plate D between the bolt-holes, and provided with the vertical slot f.

G is a double-ended spring provided with 35 a central rectangular portion g, adapted to engage with the slot f in the post F. The spring is first dropped into position in the slot, and the ratchet-wheels are then slid upon 40 the ends of the bolts. The ratchet-wheels

both have their teeth inclined in the same direction. One end of the spring engages with the teeth at the top of one ratchet-wheel, while the other end of the spring engages with the teeth at the bottom of the other 45 ratchet-wheel. The flanges e bear sidewise against the extreme end portions of the double spring, and prevent the central portion of it from coming out of the slot in the post. The spring is secured without special screws and 50 without making any hole through it, and it can be taken out of the slot and another substituted for it with great facility. The nuts are screwed upon the ends of the bolts and slip into the shallow recesses in the ratchet-wheels when nearly screwed up. The nuts 55 turn the ratchet-wheels as soon as they engage with said recesses, and are prevented from becoming unscrewed by the double spring. The ends of the spring are forced 60 back clear of the ratchet-teeth by hand when it is desired to remove the nuts.

What I claim is—

In a nut-lock, the combination, with the washer-plate provided with a vertically-slotted post, of the two ratchet-wheels provided with flanges and with recesses for the nuts to engage with, and the double-ended spring provided with a rectangular central portion and removably supported in the said slotted 65 post, and retained in position by the said ratchet-wheel flanges, substantially as set forth.

In testimony whereof I affix my signature in presence of two witnesses.

JAMES A. BRYAN.
